METERING DISPENSING CONTAINER FOR
GRANULAR MATERIAL

Jack V. Croyle, Woonsocket, and James B. Sweet, Barrington, R.I., assignors to Dart Industries Inc., Los Angeles, Calif.

Filed Jan. 3, 1972, Ser. No. 215,245

Term of patent 14 years

Int. Cl. D7—04

U.S. Cl. D7—52

FIG. 1

FIG. 2

FIG. 3

FIG. 4

FIG. 1 is a top perspective view of the metering dispensing container for granular material showing our new design;

FIG. 2 is a side elevational view thereof.

FIG. 3 is a bottom plan view; and

FIG. 4 is a top plan view.

We claim:

The ornamental design for a metering dispensing container for granular material, as shown.
